UNITED STATES PATENT OFFICE.

CHARLES J. ANDRUS, OF CINCINNATI, OHIO.

FURNACE.

SPECIFICATION forming part of Letters Patent No. 748,833, dated January 5, 1904.

Application filed May 14, 1903. Serial No. 157,098. (No model.)

To all whom it may concern:

Be it known that I, CHARLES J. ANDRUS, a citizen of the United States of America, and a resident of Cincinnati, county of Hamilton, 5 State of Ohio, have invented certain new and useful Improvements in Furnaces, of which the following is a specification.

My invention relates to a furnace of the class that has drums through which the gases from the dome or combustion-chamber circulate before passing into the flue. Its object 10 is a construction which has both this circuitous passage between the dome and likewise a short passage, with a ready means of throwing one or the other into use, and having an arrangement of drums and dome which offers a great amount of prime or heated surface evenly distributed through the jacket.

It is also an object of my invention to have 15 the connections between the drums and the combustion-chamber compact and in a form convenient for manufacturing.

In the accompanying drawings I have illustrated a furnace embodying my invention.

20 In the drawings, Figure 1 is a perspective view of a furnace embodying my invention, the casing or housing being broken away to disclose the dome and drums embodying my invention. Fig. 2 is a side elevation of the furnace with the casing broken away, the forward end of the dome and drums being shown partly in section to disclose the head-plate and damper. Fig. 3 is an end view of the same looking from the left in Fig. 2.

25 Referring to the parts, casing A, with its side outlets a and front outlets a', is of the same construction now in use, as is also the ash-pit B, fire-pot C, and the horizontal dome D.

The construction of the head-plate of the 30 dome is novel and will now be described in detail. The hollow casting E, one side e of which forms the head-plate of the dome D, is divided by a horizontally-hinged damper e' into an upper chamber e² and a lower chamber e³. Casting E has four radial forward 35 projecting flanges, the lower of which, e⁴ e⁵, lead into the chamber e³ and the upper of which, e⁶ e⁷, lead into the chamber e². Connected to the flange or arms e⁴ e⁵ are two horizontal drums F F', which run forward to the 40 front end of the furnace parallel with the dome, and connected to the arms e⁶ e⁷ are two

similar drums F² F³, which likewise run forward clear to the front of the furnace in a direction parallel with the drums. The forward 55 end of the drum F is connected to the forward end of drum F² by a vertical pipe F⁴, and the drums F' F³ are connected similarly by a vertical pipe F⁵. Damper e' has upon one end an arm g, which is connected to a rod G, running forward through the front of the casing. Chamber e² has a flange e⁸ leading to the flue above the damper e'. The head-plate e has an opening e⁹ placing the chamber e³ in communication with the interior of the dome. 60 Arms e⁴ e⁵ e⁶ e⁷ are made of a length such that the drums stand clear of dome, leaving a space between them and the dome for the free circulation of the air in the jacket.

In use when the damper is closed, as shown 65 in Fig. 2, the hot gases from the fire-pot rise up into the top of the dome and pass rearward, coming in contact with the head-plate e, and are directed thence through the opening e⁹ into the chamber e³, passing thence 70 downward through arms e⁴ e⁵ into the drums F F', thence forward into the pipes F⁴ F⁵, into the drums F² F³, thence rearward and downward into chamber e², and then into the flue e⁸.

75 It is seen that the air in the casing has a free circulation about the dome and about the drums, so that the surface of both the drums and of the dome are made prime, and that the drums leading forward to the front 80 of the furnace the air passing upward to the outlets a' likewise is brought into intimate contact with the prime heated surface, so that the front pipes convey a well-heated current, a feature which has been absent in furnaces 85 as heretofore constructed.

Should it be desired to have the communication through the dome and flue direct, as when a fresh supply of coal has been put in the furnace, occasioning smoke, the damper 90 being opened the products from the dome pass immediately from the chamber e² into the flue e⁸.

95 It is seen that the head-plate, radial arms, and the return-flue all being formed in one casting are in a most convenient form for manufacture and that they are likewise in a form in which the drums are readily connected with a minimum amount of joints.

This feature is of great importance, as in furnaces of this character it is desirous to have as few joints as possible, so as to prevent the possibility of gases passing into the air-jacket 5 and thence into the rooms.

With my construction the drums are most readily cleaned, each of the drums having at its forward end a cap *f*, which may be removed for that purpose, and the head-plate 10 is self-cleaning.

What I claim is—

1. In a furnace the combination of a combustion-chamber, a hollow casting one side of which forms the head-plate of the combustion-chamber, a damper dividing the casting into two chambers one of which communicates with the combustion-chamber, the other 15 to lead to a flue, and drums leading from one chamber of the casting into the other substantially as shown and described.

2. In a furnace the combination of a horizontal dome, a hollow casting, one side of which forms the head-plate of the dome, a horizontal damper dividing the casting into 20

an upper and a lower chamber, the upper one 25 to communicate with the flue, and the lower communicating with the dome, drums upon each side of the dome, one set leading out of the lower chamber of the casting, the other leading into the upper chamber, and pipes 30 connecting the other ends of the drums, substantially as shown and described.

3. In a furnace the combination of a horizontal dome, drums leading from the head-plate downward and forward to the front of 35 the furnace parallel to the dome leaving a space between it and the drums, similar drums leading from the front of the furnace rearward to a flue, pipes connecting the forward ends of the lower and upper drums, a 40 casing inclosing the parts having outlet-openings upon its front and sides, substantially as shown and described.

CHARLES J. ANDRUS.
